Primary Examiner — Caron D Veynar*Assistant Examiner* — Mehri Bajoul(74) *Attorney, Agent, or Firm* — Dykema Gossett PLLC(57) **CLAIM**

The ornamental design for a table, as shown and described.

DESCRIPTION

FIG. 1 is a left perspective view of a table according to my new and ornamental design when in a retracted state,

FIG. 2 is a right perspective view thereof,

FIG. 3 is a top plan view thereof,

FIG. 4 is a bottom plan view thereof,

FIG. 5 is a front side view thereof,

FIG. 6 is a rear side view thereof,

FIG. 7 is a right side view thereof,

FIG. 8 is a left side view thereof,

FIG. 9 is a left perspective view of the table when in an expanded state (includes top insert),

FIG. 10 is a right perspective view thereof,

FIG. 11 is a top plan view thereof,

FIG. 12 is a bottom plan view thereof,

FIG. 13 is a front side view thereof,

FIG. 14 is a rear side view thereof,

FIG. 15 is a right side view thereof; and,

FIG. 16 is a left side view thereof.

The features depicted in broken lines in FIG. 4-8, 12 and 15 depict environment and form no part of the claimed invention.
